US0D1075661S

(12) **United States Design Patent** (10) **Patent No.:** **US D1,075,661 S**
(45) **Date of Patent:** **** May 20, 2025**

(54) **CHARGING BOX**

(71) Applicant: **Xiamen Retone Hearing Technology Co., Ltd.**, Xiamen (CN)

(72) Inventors: **Yiquan Shi**, Xiamen (CN);
Chengxiang Zhang, Xiamen (CN)

(73) Assignee: **Xiamen Retone Hearing Technology Co., Ltd.**, Xiamen (CN)

(**) Term: **15 Years**

(21) Appl. No.: **29/882,790**

(22) Filed: **Jan. 19, 2023**

(30) **Foreign Application Priority Data**

Sep. 29, 2022 (CN) 202230649423.1

(51) **LOC (15) Cl.** **13-02**

(52) **U.S. Cl.**

USPC **D13/108**; D3/294

(58) **Field of Classification Search**

(57) **CLAIM**

The ornamental design for a charging box, as shown and described.

DESCRIPTION

FIG. 1 is a perspective view of a charging box showing our new design;

FIG. 2 is a front view thereof;

FIG. 3 is a rear view thereof;

FIG. 4 is a left view thereof, a right view being a mirror image of the left side view;

FIG. 5 is a top view thereof;

FIG. 6 is a bottom view thereof; and,

FIG. 7 is a perspective view thereof in an open configuration.

The broken lines depict portions of the charging box that form no part of the claimed design.

1 Claim, 7 Drawing Sheets
